United States Patent Office.

THOMAS FRANKLIN SMITH, OF NEW YORK, N. Y.

Letters Patent No. 102,983, dated May 10, 1870.

IMPROVED MEDICATED SOAP.

The Schedule referred to in these Letters Patent and making part of the same.

To all whom it may concern:

Be it known that I, THOMAS FRANKLIN SMITH, of the city, county, and State of New York, have invented a new and improved Medicated Soap; and I do hereby declare that the following is a full, clear, and exact description of the ingredients and composition of the same.

This invention relates to the composition and manufacture of a new and improved soap for domestic use, which combines valuable healing with powerful detergent properties.

My improved medicated soap prevents injurious effects upon the skin which often attend the use of ordinary yellow or brown soap in washing clothes, and other house-work and cleaning, and is especially valuable in preventing the hands from becoming chapped in cold weather.

In the manufacture of my improved medicated soap I employ the following substances, combined in the proportions and in the manner stated and described, to wit:

Common soap, five pounds; potash, two and one-half ounces; pearlash, one ounce; ammonia, four ounces; benzine or naphtha, eight ounces, arnica, (tincture of,) one dram; calendula, (tincture of,) one dram; rufa, (tincture of,) one dram.

The combination of these ingredients is made by dissolving the potash in one quart of water, and then boiling the common soap and pearlash together in the solution until the whole is dissolved. The mixture is allowed to cool, and the other ingredients are then all added to it, and thoroughly incorporated, while it still remains in a liquid state. When quite cold the composition becomes quite hard, so that it may be cut

up or formed into bars or cakes, ready for use in the ordinary manner, for washing clothes, scouring paint, and cleansing purposes generally.

But one of the great advantages of my improved medicated soap consists in its efficiency as a detergent in washing linen, and other kinds of fabrics, without requiring hot suds. One pound of this improved soap, added to five or six gallons of cold water, forms a solution or suds which will remove grease and dirt from clothing by merely plunging it into the solution and agitating it therein for a few minutes. Neither boiling nor rubbing of the clothes are necessary to cleanse them thoroughly; immersion and agitation in the cold solution are sufficient. The hands are thus saved from the exposure to hot water required for washing with ordinary soap, while, at the same time, the skin is protected from injury by the action upon it of alkalies, by the healing properties of the medicinal ingredients in the composition of the soap.

I do not claim the combination of the detergent ingredients of the composition hereinbefore described, for I am aware that they have been previously employed, in various proportions and combinations, for the same purpose; but

Having described my improvement,

What I claim, and desire to secure by Letters Patent, is—

The composition of a medicated soap for domestic use, formed of the several ingredients, in the proportions and manner herein described.

THOS. FRANKLIN SMITH.
